UNITED STATES PATENT OFFICE.

HARRY R. WALKER, OF ST. LOUIS, MISSOURI.

OIL BURNER.

Application filed January 26, 1925. Serial No. 4,733.

This invention relates to improvements in oil burners and consists in the novel construction hereinafter described.

An object of the invention is to provide an oil burner having a combustion chamber arranged to be mounted exteriorly of the heating element, in combination with means for atomizing oil delivered from an oil chamber into said combustion chamber, and supplying thereto a current of air to complete combustion.

Additional advantages of the structure will be apparent from the following detailed description thereof, taken in connection with the accompanying drawing, in which—

Fig. 1 is a side elevation of the complete apparatus.

Fig. 2 is a vertical sectional view.

In the embodiment of the invention illustrated in the drawing the apparatus is shown as including a cylindrical casting 1 having a tapered forward end 2 and provided with an annular flange 3, said casting being so designed as to be mounted exteriorly of a heating element such, for instance, as a furnace, by projecting the end 2 through the wall of the fire box 4 of the heating element. The member 2 is preferably arranged with a reduced outer end 5 into which an air supply passage 6 is fitted. The air is supplied through said passage 6 from a blower device 7.

The casting 1 has a segmental opening 8 in its lower portion, and a plurality of grooves 9 are formed in the wall over said openings. The purpose of the grooves is to serve as means for collecting the atomized oil delivered into the casting 1 and to act as return passages for the return of the accumulated oil back into the oil chamber.

The oil chamber consists of a cylindrical casting 10 having a clean out screw plug 11 in its bottom wall and a screw plug 12 in one of its end walls, the screw plug 12 affording means for access to the interior of the chamber for the purpose of mounting the rotor upon the driven shaft.

The opposite end wall of the casting 10 has an opening therein and mounted in alignment with said opening is a flanged pipe 13 that serves as an oil delivery pipe and also as a support for bearings 14 in which the power shaft 15 is mounted. The end of the pipe 13 is closed by a stuffing box 16.

A rotor, comprising a solid cylindrical hub 17 having a plurality of annular ribs 18 in-

tegrally formed therewith, the edges of said ribs being knurled or roughened, is mounted on the shaft 15 within the oil chamber, the rotor being held rigidly on the shaft by a nut 19 fitting over a threaded end of the shaft 15.

The oil is supplied to the oil chamber by forced feed through an oil supply passage 20, there being interposed in the line a power driven pump 21 for pumping the oil to the oil chamber. The passage 20 enters the pipe 13 through an opening in the side wall thereof and is delivered into the oil chamber 10. The oil delivery pipe is equipped with a regulating valve 22 and an oil pressure gage 23.

In order to maintain a constant level in the chamber, the oil overflow pipe 24 is connected into the chamber 10 at a level slightly above the lower part of the opening from the pipe 13 into the chamber. The overflow pipe 24 leads to a drip bucket 25 arranged to operate an automatic trip valve 26 in the feed line, thereby cutting off the feed of oil to the oil chamber when there is an over feed of oil thereto. When the valve 26 is closed the oil backs up in the line ahead of the valve 26 and is forced through a pressure valve 27 from which it may be conducted to the original source of supply.

The rotor of the pump and blower, as well as the rotor for atomizing the oil, is driven from the common shaft 15 by the motor 28.

The operation of the device is as follows: The oil is supplied through a pipe 20 to the oil chamber 10, the rotor in the oil chamber being revolved by means of the shaft 15, and the oil is carried into the combustion chamber in the form of an even spray where it is atomized by the incoming air delivered to the blower and forced into the combustion chamber of the heating element.

If, for any reason, the oil is not consumed when delivered to the combustion chamber 1, it is returned to the oil chamber and the oil is discharged through the overflow pipe 24, operating to cut off the oil supply. The flame resulting from the combustion of the mixture of oil vapor and air is forced through the opening 2 into the fire pot of the heating element for heating purposes.

I am aware that the invention may be varied in numerous particulars without departing from the spirit and scope thereof. Therefore, I do not limit myself unconditionally to details of construction and arrangement, but contemplate such variations as

may be within the scope of the appended claims.

What I claim and desire to secure by Letters Patent is:—

- 5 1. In an oil burner, a combustion chamber having a generally cylindrical form, a blower passage connected into one end of the combustion chamber and a burner nozzle at the opposite end thereof, said chamber having an elongated opening through its bottom wall, an oil chamber connected exteriorly of the combustion chamber and extending downwardly therefrom, a rotor mounted in the oil chamber so that the 10 periphery thereof extends through said opening and into the combustion chamber, and a drive shaft for rotating said rotor to cause the same to elevate the liquid from the bottom of the oil chamber into the combustion chamber.
- 15 2. In an oil burner, a combustion chamber having a generally cylindrical form, a blower passage connected into one end of the combustion chamber and a burner nozzle at the opposite end thereof, said chamber having an elongated opening through its bottom wall, an oil chamber connected exteriorly of the combustion chamber and extending downwardly therefrom, a rotor 20 comprising a series of spaced ribs, the axes of which are parallel with the axis of the combustion chamber, said rotor being mounted in the oil chamber so that the periphery thereof extends through said opening and into the combustion chamber, and a drive shaft for rotating said rotor to cause the same to elevate the liquid from the bottom of the oil chamber into the combustion chamber.
- 25 3. In an oil burner, a combustion chamber having a generally cylindrical form, a blower passage connected into one end of the combustion chamber and a burner nozzle at the opposite end thereof, said chamber having an elongated opening through its bottom wall, an oil chamber connected exteriorly of the combustion chamber and extending downwardly therefrom, a rotor 30 comprising a series of spaced ribs, the axes of which are parallel with the axis of the combustion chamber, said rotor being mounted in the oil chamber so that the periphery thereof extends through said opening and into the combustion chamber, and a drive shaft for rotating said rotor to cause the same to elevate the liquid from the bottom of the oil chamber into the combustion chamber.
- 35 4. In an oil burner, the combination with a cylindrical combustion chamber having a discharge end adapted to be connected into the fire box of a heating element and the opposite end having a connection with a blower passage and said chamber being provided with an elongated opening in its bottom wall, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 40 for said rotor.
- 40 5. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 45 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 50 for said rotor.
- 45 6. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 55 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 60 for said rotor.
- 50 7. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 65 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 70 for said rotor.
- 55 8. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 75 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 80 for said rotor.
- 60 9. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 85 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft 90 for said rotor.
- 65 10. In an oil burner, the combination with a cylindrical combustion chamber having a discharge end adapted to be connected into the fire box of a heating element and the opposite end having a connection with a blower passage and said chamber being provided with an elongated opening in its bottom wall and said combustion chamber having a series of internal annular grooves that 95 open into said opening in the bottom wall thereof, of an oil chamber rectangular in form connected to the exterior of the combustion chamber and extending downwardly therefrom and the interior of which is entirely out of alignment with the draught passing through the combustion chamber, a rotor revolvably mounted in said oil chamber and extending through the opening in said combustion chamber, and a drive shaft for said rotor.

HARRY R. WALKER.
